CLAIM

The ornamental design for a crown cap, as shown and described.

DESCRIPTION

FIG. 1 is a front perspective view of a first embodiment of a crown cap, showing my new invention;

FIG. 2 is a front elevation view thereof;

FIG. 3 is a rear elevation view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a second embodiment of the crown cap as shown in FIG. 1;

FIG. 9 is a front elevational view of the embodiment shown in FIG. 8;

FIG. 10 is a rear plan view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view of a third embodiment of the crown cap as shown in FIG. 1;

FIG. 16 is a front elevational view of the embodiment shown in FIG. 15;

FIG. 17 is a rear plan view thereof;

FIG. 18 is a left side elevational view thereof;

FIG. 19 is a right side elevational view thereof;

FIG. 20 is a top plan view thereof; and,

FIG. 21 is a bottom plan view thereof.

The broken lines shown alongside either side of the gore seams and on the top of the visor represent stitching and are part of the claimed design. The broken lines in FIGS. 7, 14, and 21 define the bounds of the claimed design and form no part thereof.
